United States Patent Office

Des. 212,506

Patented Oct. 22, 1968

212,506

DIE MEMBER

William F. Johnson, 9 Roundabout Road,
Smithtown, N.Y. 11787

Filed June 16, 1966, Ser. No. 2,703

Term of patent 14 years

(Cl. D54—4)

The figure is a perspective view of a die member showing my new design.

The undisclosed bottom side of the die member is substantially the same as the side shown.

I claim:

The ornamental design for a die member, substantially as shown and described.
